UNITED STATES PATENT OFFICE.

JOSEPH WISNIEWSKI, OF NEW ACME, WYOMING.

ROLLER-SKATE.

1,332,702.

Specification of Letters Patent. Patented Mar. 2, 1920.

Application filed May 29, 1919. Serial No. 300,528.

To all whom it may concern:

Be it known that I, JOSEPH WISNIEWSKI, a citizen of Poland, residing at New Acme, in the county of Sheridan and State of Wyoming, have invented certain new and useful Improvements in Roller-Skates, of which the following is a specification.

This invention relates to roller skates, and more particularly to skates for use on tracks.

10 The object of the invention is to provide a simple, strong and cheap skate of this character, for use by railroad men and others.

Another object is to so construct a roller 15 for a skate of this character that there will be a minimum amount of friction between it and the rail over which it passes to enable the skater to obtain maximum speed.

With the foregoing and other objects in 20 view, which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

In the accompanying drawings:—

30 Figure 1 is a side elevation of this improved skate shown applied,

Fig. 2 is an enlarged detail perspective view of the skate, and

Fig. 3 is a transverse vertical central section thereof.

In the embodiment illustrated, the skate 1 constituting this invention is shown in the form of a body member or frame here shown rectangular, although obviously the 40 contour thereof may be varied when found desirable. This body member comprises side bars 2 connected by cross bars 3 at the ends and intermediately the length thereof. These side bars 2 have longitudinally disposed spaced slots 4 for the reception of attaching straps 5 for connecting the skate to the foot of the wearer as shown in Fig. 1.

Hangers 6 are secured to the side bars 2 midway the length thereof and depend 50 therefrom, said hangers being here shown in the form of triangular plates in the tapered ends of which is supported a shaft 7. This shaft 7 is threaded at its opposite ends and projects beyond the outer faces of the 55 hangers and held in operative position by

nuts 8 and 9 disposed on opposite faces of the hangers.

A ball bearing roller 10 is mounted on the shaft 7 between the nuts 9 and is provided at its opposite ends with radially extending flanges 11 which are designed to straddle a rail R and extend downwardly on opposite faces thereof a considerable distance to hold the roller against lateral movement, and to avoid danger of its slipping off the rail. A rail tread engaging element 12 is disposed midway between the flanges 11 on the periphery of the roller as is shown clearly in Fig. 3, said element being comparatively narrow so as to provide a 70 proper support for the skate and yet have a minimum amount of frictional contact with the rail to provide for a maximum speed.

Upstanding arcuate clips 13 are arranged 75 at the rear corners of the body member of the skate, and are designed to engage the heel of the shoe of the wearer to assist in retaining the skate in operative position on the foot.

Depending from the four corners of the frame of the skate are braking elements 14 to assist in stopping when desired.

A pole P of bamboo or other light material is intended to be used in connection 85 with these skates to enable the user to retain his balance on the rail and to use it as a pusher when found desirable, and also to assist him in coming to a stop.

From the above description it will be 90 obvious that a skate of the character described will enable the user to cover a maximum mileage with the exertion of a minimum effort, owing to the slight amount of friction between the skate and the rail R 95 in connection with which it is to be used.

From the foregoing description, taken in connection with the accompanying drawings, the advantages of the construction and of the method of operation will be readily 100 apparent to those skilled in the art to which the invention appertains and while I have described the principle of operation of the invention together with the device which I now consider to be the best embodiment 105 thereof, I desire to have it understood that the device shown is merely illustrative and that such changes may be made as are within the scope of the claimed invention.

Having thus fully described my inven- 110

tion, what I claim as new and desire to secure by Letters Patent, is:—

A skate of the class described comprising a body member having hangers intermediate of its ends, a shaft mounted in said hangers, a ball bearing roller mounted on said shaft and provided with spaced radial flanges to span a track rail, and a narrow rail tread engaging element midway said

flanges extending radially beyond the perimeter of the roller. 10

In testimony whereof I affix my signature in presence of two witnesses.

JOSEPH WISNIEWSKI.
